C. H. WARTH.

PROCESS OF MAKING LIQUID FUEL;
APPLICATION FILED DEC. 29, 1913.

1,131,880.

Patented Mar. 16, 1915.

UNITED STATES PATENT OFFICE.

CHARLES H. WARTH, OF EAST ST. LOUIS, ILLINOIS.

PROCESS OF MAKING LIQUID FUEL.

1,131,880.

Specification of Letters Patent. Patented Mar. 16, 1915.

Application filed December 29, 1913. Serial No. 309,877.

To all whom it may concern:

Be it known that I, CHARLES H. WARTH, a citizen of the United States, residing at East St. Louis, in the county of St. Clair and State of Illinois, have invented new and useful Improvements in the Process of Making Liquid Fuel, of which the following is a specification.

This invention relates to improvements in liquid fuel and more particularly to a fuel of this character especially adapted for use in internal combustion engines and to the process of making this fuel.

The object of this invention is to produce a liquid fuel particularly adapted for use in internal combustion engines which will have a ready flash point but low burning point, and which will possess great explosive power and produce but little smoke.

It is the further object of this invention to produce this fuel by combining with a petroleum distillate a coal tar distillate and also blending alcohol with the two distillates.

While the preferred form of the apparatus used for making this improved fuel is illustrated upon the accompanying sheet of drawing yet it is to be understood that minor detail changes may be made therein or a different form of apparatus employing the same principal may be used without departing from the scope of this invention.

Figure 1 is a view in side elevation of a furnace employed in the preferred apparatus used in producing this improved fuel. Fig. 2 is a top plan view partly in section and with parts broken away of this furnace and the preferred form of separating tank. Fig. 3 is a view in section taken transversely through one of the furnace retorts.

In producing this improved fuel it is preferable to use a petroleum distillate having an ordinary specific gravity greater than naphtha or gasfene and the particular petroleum distillate especially adapted for this purpose is kerosene which has a low flash and a low burning point. The coal tar distillate is preferably benzol. It has been determined that while the distillates of petroleum and coal tar will readily mix yet alcohol will not mix with the petroleum distillate. I have discovered that by mixing a small quantity of the benzol as treated by this improved process with alcohol it will readily mix with kerosene so that the three

can be combined to give the desired flash and burning point.

In the preparation of this fuel it is necessary to treat both the kerosene and benzol in a certain manner, as the commercial kerosene contains a certain amount of asphalt, carbon and greasy substances held in solution in the distillate and should be removed to give the refined product a low boiling point and more complete combustion. The commercial benzol contains in solution a percentage of the tar from which it is made and burns with a heavy smoke, which is most undesirable in liquid fuel of this character, and the tarry substances should be removed so that the refined product will be much lighter, more volatile, and free from smoke.

The process for refining the kerosene consists in passing the oil to be treated through a double coil made by placing a smaller pipe of any desired size within the larger pipe leaving a space between the two pipes which space is filled with steam, the pipes are then formed into a coil of any desired shape and placed within the furnace in which the heat is applied to the outer pipe of the coil causing the coil contained within the inclosed pipe to be subjected to a high degree of heat and disintegrate or break up the globules of the oil. The distillate when so treated is then placed in a suitable settling tank having a temperature below that at which the heaviest material will boil, the distillate will separate and the heaviest portion will precipitate and remain in the separator allowing the lighter distillate to pass over into a second separator of the same character, and then on to a condenser. The light oil thus produced is then treated in the ordinary way of treating kerosene to sweeten and then remove the remaining heavy substances.

The method of refining the benzol is the same as that used in refining the kerosene and the refined product of the benzol will hereinafter be referred to in this application as benzolin. The refining of the kerosene and the benzol may take place separately and the refined products mixed as they will readily combine and form a chemical combination or, as preferred, the kerosene and benzol may be first combined in the proportions to give the desired flash of burning point and then refined together in the

a single operation. When it is desired to blend alcohol with the refined kerosene and benzolin a small quantity of the benzolin is mixed with the alcohol and then the two 5 will combine with the refined kerosene.

The drawing illustrates one form of apparatus for refining the kerosene and benzol. This apparatus comprises a furnace 1 through the side walls of which passes a 10 plurality of retorts 2 which are held suspended above the fire box of the furnace. The retorts are closed at each end and preferably extend a slight distance beyond each side wall.

15 An oil pipe or conduit 3 leading from a source of oil supply, not shown, passes through one end of the retort at one end of the series, continues through, passes out the other end, and is then brought back again 20 through the retort and over into the next adjacent retort, and passes through this retort in the same manner and through each one in the series. The oil pipe from the last retorts is connected to a separating tank 4 25 hereinafter described.

A steam pipe 5 leading from a source of steam supply, not shown, enters one end of the end retort of the series and the steam after passing about the oil pipe is then lead 30 by a pipe 6 into the next adjacent retort and so on through the entire series. The steam pipe 7 from the last retort enters the separating tank 4.

The oil pipes within the retorts are preferably oblong in cross section, as indicated by 3^a in Fig. 3. The superheated steam surrounding the oil pipe 3 serves to protect the bottom of the retorts 2 from burning out and the oil from scorching or becoming too 40 hot and forming gas. Thermometers 8 are preferably placed in the oil pipe where it passes from one retort to the other. A sufficient number of retorts are used to insure a sufficient length of oil pipes inclosed 45 therein to impart the desired degree of heat and the exact degree of heat may be regulated by inspecting the thermometers to cause the oil to disintegrate and pass over in a form of a vapor to the separator 4.

50 The separator 4 is a closed vessel to which is lead through a pipe 9 the vapor from the oil pipe of the last retort. A coil within the separator is connected at one end with the steam pipe 7 and the length of this steam 55 coil is such that the temperature within the separator 4 is just low enough to cause the heavy part of the vapor to condense and precipitate, the lighter vapors advancing through the pipe 11 into a second separator 60 12. The other end of the steam coil 10 is connected by a pipe 13 to a similar steam

coil 14 within the second separator 12. A drain cock 15 is provided at the bottom of the separators for drawing off the condensed liquids.

65

The second separator 12 is of similar construction to the first separator 4 and the temperature in the second separator is regulated so as to condense any remaining non-combustible matter in the distillate. The 70 vapor in the second separator is conducted by the pipe 16 to a condenser of any desired form, not shown, from which the refined distillate is drawn in liquid form.

As previously stated the benzol may be 75 treated separately in the same manner when it is desired to blend alcohol with the kerosene. In such case the alcohol is mixed with the refined benzol or benzolin in the proper proportions and then added to the refined 80 kerosene.

When it is desired to use a mixture of the two distillates alone, the kerosene and benzol may be mixed in the proper proportions and the mixture run through the pipe 3 in the 85 retorts, through the settling tanks 4 and 11, and then condensed to form the liquid fuel.

What I claim is:

1. The process of producing a liquid fuel comprising the treatment of kerosene and 90 benzol with heat sufficient to vaporize them, subjecting the vapor to a lower degree of heat sufficient to condense the heavier properties and then condensing the remaining vapors.

95 2. The process of producing a liquid fuel comprising the passing of kerosene and benzol through a pipe leading back and forth through a retort containing superheated steam subjected to the heat of the furnace, 100 leading the vapor so formed into a separating tank containing a steam coil and having a sufficient lesser degree of heat than the retort, whereby certain of the heavier properties of the vaporized oil are condensed, 105 leading the vapor therefrom into a second separating tank having a lesser degree of heat than the first, whereby the remaining heavier properties and foreign matter are condensed, and condensing the remaining 110 vapor.

115 3. The process of producing a liquid fuel comprising the combining of a petroleum distillate with a coal tar distillate, initially vaporizing the combined liquids in small quantities, subjecting the vapor so formed to successive lower degrees of heat, and then condensing the remaining vapor.

CHARLES H. WARTH.
